US0D1041829S

(12) **United States Design Patent** (10) **Patent No.:** **US D1,041,829 S**
(45) **Date of Patent:** **** Sep. 17, 2024**

(54) **SHOE MIDSOLE**

(71) Applicant: **adidas AG**, Herzogenaurach (DE)
(72) Inventors: **Moritz Hoellmueller**, Fuerth (DE);
Timon Kuhlenkamp, Nuremberg (DE)
(73) Assignee: **adidas AG**, Herzogenaurach (DE)
(**) Term: **15 Years**
(21) Appl. No.: **29/814,397**
(22) Filed: **Nov. 5, 2021**
Related U.S. Application Data

(63) Continuation of application No. 29/722,503, filed on Jan. 30, 2020, now Pat. No. Des. 938,145.

(57) **CLAIM**

The ornamental design for a shoe midsole, as shown and described.

DESCRIPTION

FIG. 1 is a side view of a shoe midsole.

FIG. 2 is another side view of the shoe midsole of FIG. 1, from the opposite side shown in FIG. 1.

FIG. 3 is a rear view of the shoe midsole of FIG. 1.

FIG. 4 is a front view of the shoe midsole of FIG. 1.

FIG. 5 is a top view of the shoe midsole of FIG. 1.

FIG. 6 is a bottom view of the shoe midsole of FIG. 1; and,

FIG. 7 is a perspective view of the shoe midsole of FIG. 1.

The lightened areas surrounded by dashed lines show portions of the shoe midsole that form no part of the claimed design.

1 Claim, 6 Drawing Sheets
